UNITED STATES PATENT OFFICE.

OWEN M. GALLOWAY, EDWARD B. WHITE, AND ADAM D. NEPTUNE, OF MOUNTAYR, IOWA.

TELEPHONE CUT-OUT AND SWITCH.

No. 802,387.

Specification of Letters Patent.

Patented Oct. 24, 1905.

Application filed September 1, 1904. Serial No. 223,035.

To all whom it may concern:

Be it known that we, OWEN M. GALLOWAY, EDWARD B. WHITE, and ADAM D. NEPTUNE, citizens of the United States, residing at Mountayr, in the county of Ringgold and State of Iowa, have invented certain new and useful Improvements in Telephone Cut-Outs and Switches; and we do declare the following to be a full, clear, and exact description of the invention, such as will enable others skilled in the art to which it appertains to make and use the same.

Our invention is an improved telephone cut-out and switch for use on a private telephone-line or in connection with two of such lines; and it consists in the construction, combination, and arrangement of devices hereinafter described and claimed.

In the accompanying drawings, Figure 1 is a front or outside elevation of a telephone cut-out embodying our invention. Fig. 2 is a side elevation of the same; and Fig. 3 is a sectional view of the same, taken on the plane indicated by the line *xx* of Fig. 1. Fig. 4 is a detail sectional view taken on the plane indicated by the line *yy* of Fig. 1.

On the base 1 is a conducting-strip 2, having a binding-post 3 at its lower end for the attachment of an instrument-wire *a*. To the other end of the conducting-strip is connected a switch-arm 4, which has an operating pivot-rod 5 of sufficient length to extend through a wall of a building and at the inner end of which operating-rod there is a button 6, by means of which said rod, and hence, also, the switch-arm, may be turned. The base is designed to be secured to the outer side of a building, and the switch-arm is designed to be operated from the inner side of the building by turning the said button.

On the outer side of the base and on opposite sides of the conducting-strip 2 are binders 7 8, which are provided, respectively, with contacts 9 10 and with connecting spring-jaws 11 12. Ground-connectors 13 14, having conducting spring-jaws 15 16, the latter being respectively opposite the jaws 11 12 and appropriately spaced therefrom, are secured on the base. Between the said pairs of jaws 11 15 and 12 16 are pairs of carbon plates 17, between which are secured strips 18 of perforated mica or other suitable non-conducting material.

A bell-connector 19 for a bell *B* is secured

to the base. On the inner side of the latter is a circuit-closer 20, comprising a contact-piece 21 and a contact-spring 22. Said contact-piece is connected by a conducting-wire 23 (indicated by a dotted line in Fig. 1) to the binder 8, and said contact-spring is connected by a conducting-wire 24 (indicated by a dotted line in Fig. 1) to the binder 19. Said spring is normally in contact with the contact-piece to establish electrical connection between the connector or binder 19 and the binder 8.

On the outer side of the base is a spring 25, here shown as a bowed spring, having longitudinal slots 26 in its ends engaged by the studs or pins 27, which secure the said spring on the base. From the inner side of the said spring, at the center thereof, projects a spur 28, which extends through an opening in the base, and when the spring is pressed toward the base engages the contact-spring 22 and moves the free end of the latter from the contact-piece 21, thereby breaking electrical connection between the connector or binder 19 and the connector or binder 8. The switch-arm may be moved in position to engage and thus depress the spring and it may also be turned into engagement with either of the contacts 9 10.

The instrument is connected to the binder or connector 3. A line *c* is connected to the binder or connector 7. A line *b* is connected to the binder or connector 8. Each of the binders 13 14 has a ground connection, and the binder 19 is connected to an extension-bell.

In order to talk on line *b*, the switch-arm 4 should be turned into contact with the contact-spring 10. To use the line *c*, the switch-arm 4 is turned into contact with the contact-spring 9. The instrument may hence be used on either of the lines. To protect the instrument and the bell *B* from injury by lightning, the switch-arm should be turned into engagement with the spring 25 to break the circuit at 20. A current of high potential over either of the lines will be grounded, as will be understood. The bell on the instrument rings when the call comes on the line *c*, and the bell *B* or extension-bell rings when the call comes over the line *b*, so that our improved cut-out and switch enables a single instrument to be used on two lines and also affords perfect protection to both instrument and bell.

Having thus described our invention, what

we claim as new, and desire to secure by Letters Patent, is—

1. The combination of line conductors, an instrument-conductor, a switch-arm to which the instrument-conductor is connected, said switch-arm being adapted to include the instrument in circuit with either of the line conductors, a bell-conductor connected to one of the line conductors and including a normally closed make-and-break, the latter being opened by the switch-arm when said switch-arm is out of connection with both of the line conductors.

2. The combination of line-circuits, each having a lightning-arresting ground connection, an instrument-conductor, a switch-arm to which the instrument-conductor is connected, said switch-arm being adapted to include the instrument in circuit with either of the line conductors, a bell-conductor connected to one of the line conductors and including a normally closed make-and-break, the latter being opened by the switch-arm when said

switch-arm is out of connection with both of the line conductors.

3. The combination of line conductors, an instrument-conductor, a switch-arm to which the instrument-conductor is connected, said switch-arm being adapted to include the instrument in circuit with either of the line conductors, a bell-conductor connected to one of the line conductors and including a normally closed make-and-break, and a spring having a pin to open the make-and-break, said spring being operated by the switch-arm when the latter is out of connection with both of the line conductors.

In testimony whereof we have hereunto set our hands in presence of two subscribing witnesses.

OWEN M. GALLOWAY.
EDWARD B. WHITE.
ADAM D. NEPTUNE.
